Primary Examiner — George D Kirschbaum*Assistant Examiner* — Joseph Kukella(74) *Attorney, Agent, or Firm* — Terrile, Cannatti, Chambers & Holland, LLP; Robert W. Holland(57) **CLAIM**

I claim the ornamental design for a safety wand, as shown and described.

DESCRIPTION

FIG. 1 is a front upper perspective view of the safety wand comprising the present invention;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

Broken lines shown in the drawings illustrate portions of the safety wand, and form no part of the claimed design.
